BERNARD ORMONT, OF NEW YORK, N. Y., ASSIGNOR TO BERNARD ORMONT ASSOCIATES, INC., OF NEW YORK, N. Y., A CORPORATION OF NEW YORK.

PROCESS FOR PRODUCING GASOLINE AND OTHER HYDROCARBONS.

Application filed May 27, 1921. Serial No. 473,193.

This invention relates to a process for producing lighter hydrocarbons, such as gasoline for example, from heavier hydrocarbons, and has for its object to provide a process which will be more efficient in operation than those heretofore proposed.

With these and other objects in view, the invention consists in the novel steps and combinations of steps constituting the process, all as will more fully appear below and be particularly pointed out in the claims.

Referring to the accompanying drawings forming a part of this specification, in which like numerals designate like parts in all the views:

Figure 1 is a diagrammatic elevational view of an apparatus constructed in accordance with the present invention and suitable for carrying out the present process;

Figure 2 is a diagrammatic end elevational view, partially broken away, of one of the furnaces or heating chambers illustrated in Figure 1;

Figure 3 is a diagrammatic horizontal cross sectional view taken approximately on the line 2—3 of Figure 2, looking downward;

Figure 4 is a detail vertical sectional view, taken approximately on the line 4—4 of Figure 3, looking in the direction of the arrows;

Figure 5 is a central vertical sectional view through one of the condensing tanks and one of the receiving tanks illustrated in Figure 1; and

Figure 6 is a diagrammatic plan view of one of the cooling coils employed in the condensing tank shown in Figure 5.

1 indicates an oil supply pipe provided with the branches 2 and 3 controlled respectively by the valves 4 and 5 leading into the upper portions of the tanks 6 and 7, as will be clear from Figure 1. A pipe

45 8 provided with the valve controlled branches 9 and 10 is connected to the lower portion of the said tanks 6 and 7 and is adapted to supply water or other fluid under pressure to the interior of the said tanks.

50 Said tanks are each provided with a draw off or discharge pipe 11 whereby they may be drained whenever desired.

Leading from the top of the said tanks 6

and 7 are the oil discharge pipes 12 and 13, respectively controlled by the valves 14 and 15 and connected to the oil feed line or pipe 16, which is adapted to feed the hydrocarbon oils into the furnace 17, in a manner to be disclosed. The said furnace 17 as is best illustrated in Figures 1, 2, and 3, comprises a suitable structure 18 in which are embedded a plurality of rows of pipes 19, 20, 21, 22 and 23 arranged substantially as shown.

The intermediate portions of the pipes of each row, such as 19, for example, see Figures 2 and 3, may rest upon suitable transversely extending supports 125, rotatably mounted in the bearings 126, embedded in the furnace walls, and the ends of said pipes are connected in series by means of the T connections 25 provided with the short nipples 26, as will be readily apparent, but such T connections in the rows 20, 21, and 22 are only shown on the rear end of the furnace, in Figures 1 and 2. The ends of the T connections which project through the walls of the furnace structure 18 may be closed by suitable plugs 27, which, of course, may be removed, permitting the insertion of a cleaning device should it be necessary or desirable to clean out the interior of the pipes such as 19.

The oil supply pipe 16 is connected to one end of the upper row or series of pipes 19 as at 28 and the other end of the said series of pipes 19 is connected to the pipe 30 provided with a T connection 31, one leg of which is connected to the second row or series of pipes 20 and the other leg of which is connected to the pipe 32 leading from the lowermost row of pipes 23, for a purpose to be more fully disclosed below.

The other end of the row of pipes 20 is connected by a pipe 33 to one end of the row of pipes 21 and the other end of this latter row of pipes is joined as by a pipe 34 to one end of the row of pipes 22, as will be clear from Figure 2. The outlet end of this last mentioned series of pipes 22 is connected to a pipe 35 which may lead to a second furnace or heating chamber 36, substantially similar in design to the furnace 17 just described, in so far as the general construction is concerned, although its pipe connections are somewhat different. That is to

say, in the furnace 17 the lowermost row of pipes 23 is connected at one end to a pipe 37 provided with a valve 38 through which water may be introduced from the water supply pipe 8 into the said pipes 23. The other end of this series of pipes may be connected by the pipe 32 to the T member 31, above described, whereby steam and water vapors, generated in the series of pipes 23, may be mixed with the oil vapors from the series of pipes 19, all in a manner to be more fully disclosed below. On the other hand, the various pipes in the furnace 36 are all connected in series, or, in other words, the vapors passing through the pipe 35 from the furnace 17 are led to the uppermost row of pipes 40, from whence they pass into the next row of pipes 41 and then successively through the succeeding rows of pipes 42, 43, and 44, emerging finally through the pipe 45 from the lowermost series 44, as will be clear from Figure 1.

The said furnaces or heating chambers 17 and 36 may be fired in any suitable manner, not shown, as, for example, by solid, liquid, or gaseous fuel.

The pipe 45 leading from the lowermost series of pipes in the furnace 36 conducts the vapors to a condensing tank 46, the said pipe being provided with a plurality of inlets 47, 48 and 49 into said tank. These said inlets are preferably arranged substantially as shown; and serve to introduce the vapors into the said tank 46 at various levels for a purpose which will appear more fully below. Each of the said inlets is provided with a valve, whereby any one, two, or all of them may be opened or closed at the same time as varied working conditions require. The said tank 46 is provided on its interior with a plurality of perforated baffle plates 50, see Figure 5, preferably located at its middle portion.

Above the uppermost of these said baffle plates 50, there is provided a cooling or heating coil 51 comprising a plurality of flat spiral coils 52 joined in series as shown, and adapted to be supplied at the uppermost end from a pipe 53, as will be clear from said Figure 5. The outlet end of the said cooling member 51 is connected as by a pipe 54 to a lower cooling or heating member 55 constructed of flat spiral coil members 56 in a manner similar to the upper member 51, just described. The outlet end of this lower cooling member is connected as by a pipe 57 provided with a valve 58, to a suitable discharge pipe 59, substantially as shown. 60 indicates a water supply pipe joined to the water supply pipes 8 and 37, see Figure 1, and connected as by the valved connections 61 to the inlet pipe 53, whereby cooling water may be introduced into the said cooling members 51 and 55, while 62 represents a steam supply pipe, joined as by the branch pipe 63, having a valve 64 to

the said inlet pipe 53, whereby steam may be admitted into the said coils 51 and 55 to heat the vapors should the operating conditions require heating rather than cooling.

Such of the vapors as are introduced into the tank 46 and are not condensed by means of the cooling pipes therein, may escape therefrom through the pipe 65, provided with the valve 66, which pipe 65 is provided with a plurality of valved branches 67, 68 and 69 leading into a tank 70, which is or may be similar in all respects to the tank 46, just disclosed.

In like manner such of the vapors which are introduced into the said tank 70 as are not condensed, may be led by means of a pipe 71 to a third tank 72 and should there still be any uncondensed vapors after the treatment in this said tank, they could well be led to fourth, fifth and sixth tanks, if so desired. I have only illustrated three condensing tanks, but it is to be understood that as many tanks may be provided as are necessary to effect a substantial total condensation of the vapors at atmospheric pressure.

The tanks 70 and 72 may also be provided with suitable cooling members 73, 74, 75 and 76 similar to the coils 51 and 55, with which the tank 46 is provided, and these cooling coils may be connected to the water supply pipe 60 as by the valved connections 77 and 78 respectively. They may also be connected to the discharge pipe 59 by the valved connections 79 and 80 respectively, as will be clear from Figure 1.

Located adjacent each of the condensing tanks 46, 70 and 72 is a collecting tank such as 81, 82 and 83. The tank 46 is connected to the tank 81 as by the pipe 84, while the tank 70 is connected to the tank 82 by the pipe 85 and the tank 72 is connected to the tank 83 by the pipe 86. These last mentioned connections 84, 85 and 86 constitute means whereby such hydrocarbons as are condensed in the tanks 46, 70 and 72 respectively may be transferred into the collecting tanks 81, 82 and 83, as will be readily apparent.

Should any of the vapors remain uncondensed upon passing through the last tank of the series, such as 72, they may escape therefrom through a pipe 87 leading into the upper portion of the collecting tank 83. In like manner, said vapors may pass from tank 83 through a pipe 88, into the collecting tank 82 and through a pipe 89 into the tank 81, and from tank 81 any vapors may pass by way of a pipe 90 to and through a condensing coil 91 associated with a compressor 92 adapted to compress the still uncondensed vapors in order to liquefy them and obtain therefrom additional condensate. Said condensing coil 91 may, if desired, be cooled by any suitable means, not shown.

The tanks 81, 82, and 83 are provided with

valved connections 94, 95, and 96 respectively, connected to the pipe 97, which latter is connected as at 98 to the pipe 90 so that the vapors may be individually discharged from any of the said tanks 81, 82 or 83 directly to the condenser 91 without passing through the succeeding tanks. The said tanks 81, 82 and 83 are further provided with the outlet pipes 100, 101, and 102 respectively leading to receiving pans, not shown, whereby the condensed hydrocarbons may be removed therefrom.

103 indicates a common return pipe which is connected to all of the tanks 46, 70, 72, 81, 15 82 and 83 as by the valved connections 104, 105, 106, 107, 108, and 109 respectively, whereby any residues which accumulate in these said tanks may be returned to the pipe 16 and fed back through the furnaces 17 and 20 36 to be reworked. In like manner, the tanks 46, 70 and 72 are provided with suitable draw-off pipes 110, 111, and 112 through which any residues may be entirely withdrawn from the system.

25 As will presently appear from the description of the operation of the apparatus, it may sometimes happen that the temperatures within the tanks 46, 70 and 72 may be too low for the efficient operation of the 30 process. That is to say, this being essentially a process of fractional condensation, certain predetermined temperatures should be substantially maintained in each of the 35 said tanks, at which temperatures certain well known hydrocarbons will liquefy, while others will remain in the gaseous state. These temperatures may be indicated by suitable thermometers 115 carried by the 40 said tanks and should they fall below the minimum necessary to condense the particular hydrocarbon desired in that tank, the cooling water passing through the coils such as 51, 55, 73, 74 and 75 and 76 may be cut off by means of the valves 61, 77 and 78 and 45 steam may be passed through the said coils 51, 55, etc., from the steam line 62 through the various valved connections 63, 116 and 117. Each of the said tanks 46, 70 and 72 50 may also be provided with a pressure gauge such as 118 in order that the pressures within the tanks may be known at all times, although the process is normally carried on at substantially atmospheric pressure.

The details of carrying out the process 55 through the use of the apparatus disclosed will be clear from the foregoing, but may be briefly summarized as follows:

It is preferable, although not absolutely 60 essential, that the entire apparatus be first heated up to substantially its normal operating temperature, and to this end water may be first passed into the series of pipes 23 from the pipe 37, and there vaporized by the 65 burning of fuel within the furnace 17. The steam thus formed is permitted to pass

through the pipes of both of the furnaces 17 and 36, and through the entire train of pipes and tanks until each of the units is heated up to its proper temperature. The condensed steam may be withdrawn from the tanks through the various drain pipes 104, 70 105, 106, 107, 108, and 109.

Oil from any suitable source, not shown, is now admitted to the tanks 6 and 7 from the pipe 1 through its valved branches 2 and 3, while water under pressure enters the lower portions of said tanks from the pipe 8 through its valved connections 9 and 10. The pressure of the water thus introduced into the said tanks will force the oil through the pipes 12 and 13 into and through the pipe 16 to the uppermost coil or series of pipes 19 in the furnace 17, where it is vaporized. The flow of water from the pipe 37 into the row of pipes 23 being continued, the formation of steam within the said pipes 23 will continue, and the oil vapors passing from the row of pipes 19 into the connection 30 and the water vapors escaping from the pipes 23 by way of the connection 32, will meet and mix at the T connection 31 and will then pass into the series of pipes 20 to be further heated. The said mixed vapors will pass through this said series 20, through the connection 33 into and through the pipes 21, through the connection 34 into and through the pipes 22, from whence they will escape by way of the pipe 35 leading to the uppermost series of pipes 40 to the second furnace 36. In like manner the mixed vapors will pass successively through the rows of pipes 41, 42, 43 and 44 of the said furnace 36 and will finally escape therefrom into the pipe 45 through which they will pass to the valved connections 47, 48 and 49 leading into the condensing tank 46, as was above disclosed.

The question as to which of these said connections 47, 48 or 49 or how many of them, shall be used depends upon the temperature it is desired to maintain in the tank 46, which in turn will depend upon the particular hydrocarbon it is desired to produce therein. That is to say, it is evident if the vapors enter the said tank 46 through the connection 47 only, they will remain within the tank only a relatively short time before leaving through the pipe 65 and the lower portion of said tank 46 will be completely cooled. On the other hand, should it be desired to maintain a higher temperature within the said tank 46, connection 47 may be closed and 48 opened, or both 47 and 48 may be closed and 49 opened. In either event, the vapors will be compelled to remain for a longer period of time within the tank and will be forced to give up more of their heat units, so that the temperature of the tank may be increased to the desired point.

On the other hand, if the temperature

within the tank 46 is maintained too high when the gases are entering through the connection 47 alone, it may be reduced by the admission of cooling water into the coils 51 and 55 as will be readily apparent.

Should it be found in operation that some of the products condensed in the tank 46 should not properly come down there, due to the fact that too low a temperature is attained coils 51 and 55 instead of being utilized as cooling coils may be connected by means of the valved connections 63 to the steam pipe 62 and steam passed through the said coils whereby the temperature of the tank may be suitably increased.

The hydrocarbon liquids which condense in the tank 46 may be withdrawn therefrom through the pipe 84 into the collecting tank 81 from whence they may be withdrawn as desired through the pipe 100 into any suitable receiving pans, not shown. Such gases as are not condensed within the tank 46 will pass by way of the pipe 65 and its connections 67, 68, and 69, or any of them, into the second tank 70, where the same temperature control may be had as was disclosed in connection with the tank 46 and in which certain additional hydrocarbons will be condensed. These hydrocarbons may be transferred to the collecting tank 82 through the connection 85 and they may be withdrawn from the said tank 82 into a receiving pan through the pipe 101. Any remaining gases which have not been condensed may leave the tank 70 through the pipe 71 and be introduced into the third tank 72 through the connections 120, 121, and 122, or any of them, and the same process repeated. The liquids which are condensed are withdrawn from the tank 83 through the pipe 86 and escape therefrom to receiving pans through the pipe 102. This cycle, of course, may be repeated as many times as necessary, depending upon the number of condensing tanks such as 46, 70 and 72 which are provided.

The liquids which are condensed in the tank 46 will be of a very high specific gravity and corresponding boiling points, while those which are condensed in the tanks 70 will have somewhat lower specific gravities and lower boiling points, and those which are condensed in the tank 72 will have still lower specific gravities and boiling points. This decrease in specific gravity and in boiling point will continue to the last tank, wherein the liquids having the lowest specific gravities and boiling points will be produced.

It will be noted that the connections 84, 85 and 86 leading from the tanks 46, 70 and 72 respectively into the tanks 81, 82 and 83 are located some distance above the bottoms of the said tanks. This permits the condensed liquids to accumulate within the

tanks 46, 70 and 72, until they reach a certain level, whereby any impurities which may be present such as water, may be permitted to settle to the bottom. The purest portions of the condensate will, of course, rise to the top and will be the portions which pass into the collecting tanks such as 81 through the connections such as 84. The impurities may be withdrawn from the tanks through the valved connections such as 104, 105, 106, into the pipe 103 through which they may return to the pipe 16 leading back to the furnace 17 where they may be re-worked.

On the other hand, if said impurities have no commercial value they may be entirely withdrawn from the tanks through the draw-off pipes such as 110, 111, and 112.

It will thus be seen by following the process above outlined, I am enabled to accomplish the following advantageous results:

First, by controlling the flow of oil and water through the pipes of the furnaces 17 and 36, the temperature of the gases therein may be maintained at any desired point, preferably not exceeding, say, 750° F. This temperature as will be appreciated, is exceedingly low, for this type of process, and tends to lessen the deposition of carbon in the furnace pipes while permitting the formation of hydrocarbons of high Baume gravities and low boiling points.

Second, it should be noted that the pressures which may be used are approximately atmospheric, the gases being forced through the entire train only by the pressure generated in their production.

Third, owing to the fact that a relatively small quantity of liquid is in the apparatus at any one time, the danger of explosion is minimized; and

Fourth, the process may be run continuously, due to the fact that the residues are continuously reworked and the deposition of carbon in the furnace pipes is practically eliminated, so that the apparatus need seldom or never be shut down for cleaning.

Fifth, owing to the peculiar construction of the furnaces 17 and 36, should any portion of the coils thereof become clogged, burnt out, or otherwise inoperative, it is a comparatively simple matter to provide suitable by-passes and continuously run the furnaces while the injured parts are removed and replaced.

Sixth, since the oil is heated in the furnace to a temperature sufficient to vaporize the same, and since the temperature of the vapors are under absolute control in the condensing tanks by the admission of water or of steam as may be required, it is evident that the pressure of the vapors in said tanks, and therefore in the system, will likewise be regulated by the temperature maintained in said tanks, or in other words, said

pressure will be controlled by the rate of condensation of said vapors in said tanks, which is under the control of the operator.

Seventh, it is thus evident that this process involves the heating of the oil to vaporize the same and the utilization of the pressure produced by said heating action to force the vapors produced into and through cooling zones to condense the vapors. Therefore, since the passage of the oil through the apparatus is along a considerable length of piping, or through valved passages, there is, of course, a greater or less amount of resistance offered to the passage of the vapors and a very appreciable pressure can be and is usually maintained in the system, although the ends of said piping or passages are, or may be, open to the atmosphere at all times. But this said pressure in the system is very much less than is the pressure maintained in other prior systems, and in this case needs seldom, if ever, be above, say 50 or 75 pounds. As a matter of fact, I find in actual tests that it need seldom be above 50 pounds, and I have found excellent results when the pressure in the system is only 25 pounds, or 15 pounds, or even as low as 10 or 5 pounds, or less.

Eighth, another important feature of this invention resides in the fact that the pipes 19 and 40 and other parts of the furnaces containing steam such as the coils 20, 21 and 22, for example, are or may be made of an alloy of iron and silicon, containing, preferably, say from 3% to 10% or higher, of silicon, for it is found that the silicon apparently acts as a catalyst and improves the quantity of lighter hydrocarbons produced.

I find substantially the same improvement can also be had if an alloy of calcium, silicon, and iron or steel is employed. In practice, however, a very high silicon steel is found to be very satisfactory and the parts are replaced when they become corroded.

Ninth, a still further important feature of this invention resides in the fact that when the vapors of oil and steam meet, that portion of the oil that is still unvaporized passes down the pipe 32 and through some of the pipes 23 to meet water in its liquid condition whereupon the heat of the furnace 17 vaporizes the water, or produces steam while it is substantially in contact with said oil.

I have found from actual tests that the effect of this newly formed steam, or what I call nascent steam, upon the heated oil, produces a surprising result in that it will cause a vaporization of all of the heavier ends of the original oil into oil vapors, which after being passed on through the system along with the first mentioned vapors are transformed into hydrocarbons of very much less specific gravities and of a commercial value

which is not the case when said heavier ends are treated with steam or heat alone.

That is to say, I can even take the residue oils or the slops, so called in the refinery, and split them up into said lighter hydrocarbons. These said residue oils require a very high temperature for vaporization under prior treatments; and if it is attempted to vaporize the same by the ordinary methods, an excessive gas loss results, and their products are of no commercial value. If treated with nascent steam by my method, on the other hand, the properties of the nascent steam seem to convert them into vapors which can for example be readily condensed into gasoline, kerosene and lubricating oil.

Thus it will be seen that some of the oil passed to the furnace 17 through the pipe 16, will not be vaporized in the series of piping 19, with the result that the unvaporized oil will pass the T connection 31, flow downwardly through the pipe 32 and to and into the piping 23 in a direction from left to right as seen in Fig. 1, which is a direction opposed to the direction of flow of the water entering the furnace through the pipe 37 and which likewise reaches and flows through the pipe 23. In other words, it will be seen that the piping 23 is adapted to have water and oil flow therethrough in opposite directions or toward each other, with the result that there will be created in said piping 23 a region or area where said water will be turned into steam by the heat under the piping 23. The rate of flow of the oil in said pipes is controlled, with the resultant discovery that this process allows the oil to flow to the said region in which the water is entirely vaporized, or in other words, allows the oil to substantially meet the water in its liquid condition. Further, I have disclosed above that in this region there is produced what I term nascent steam, which is that condition of steam existing at the instant of the change of water from the liquid to the vapor state. Also I have discovered that it is due to this nascent steam that all of the oil is vaporized including the heavier ends thereof, and at a temperature which is considerably below the temperature heretofore found necessary to vaporize said heavier ends, thus making for improved production of oils from crude oil.

In the preceding description I have referred to the fact that the oil meets the water in its liquid condition, and also I have mentioned that the oil vapors mix with the water vapors. Such phraseology was used in the absence of proper terms which would exactly describe what takes place in my process. In other words, it is old in the art to mix oil and water, and it is old to mix oil with steam, and still further it is old to mix oil

vapors with steam, but what I claim as my discovery is the vaporization of all of the crude oil including the heavier ends thereof at temperatures below those heretofore found necessary and due to the presence of nascent steam. The oil in my process starts vaporizing in the upper piping 19, and it is these vapors of course which pass over to the second furnace and into subsequent condensers through the piping 20, 21 and 22. On the other hand, the unvaporized oil passes the T 31 and is completely vaporized in the above mentioned region in which nascent steam is produced. In other words, all of the oil which reaches this region is vaporized at a temperature normally insufficient to vaporize the heavier ends of said oil, due to the nascent steam in, and the heat of, said region.

Following up this discovery I have repeatedly worked the foregoing process starting with crude oils, drawn off the residue from the tanks 46, 70 and 72, through the pipes 104, 105 and 106 respectively. Said residues were then passed back to furnace 17, through pipes 103 and 16.

It is obvious that those skilled in the art may vary the details of construction and the arrangement of parts constituting the apparatus, as well as the precise mode of carrying out the process without departing from the spirit of the invention, and therefore, I do not wish to be limited to the above disclosure except as may be required by the claims.

What I claim is:—

1. The method of vaporizing a hydrocarbon oil which consists in heating said oil to a vaporizing temperature insufficient to completely vaporize the same; independently heating water to produce a region of nascent steam; conveying the unvaporized oil to said region where said oil is completely vaporized; and subjecting the resultant mixture of oil vapors and steam to additional heating.
2. The method of completely vaporizing a hydrocarbon oil which consists in continuously vaporizing the lighter ends of said oil out of contact with water; and subjecting the unvaporized oil to the action of heat and nascent steam to completely vaporize the same while the lighter ends are being so vaporized.
3. The method of completely vaporizing a hydrocarbon oil in a heater which con-

sists in continuously vaporizing the lighter ends of said oil out of contact with water; conveying only the unvaporized oil to a region of nascent steam; and subjecting the unvaporized oil to the action of heat and nascent steam to completely vaporize the heavier ends of said oil, while the lighter ends are being so vaporized.

4. The method of vaporizing a hydrocarbon oil which consists in introducing said oil and water into a heater at separate points; vaporizing the lighter ends of said oil while creating a region of nascent steam out of contact with said lighter ends; leading the unvaporized oil to said region to completely vaporize the same; and conveying the combined vapors of all of said oil and water out of said heater.

5. The method of vaporizing a hydrocarbon oil which consists in introducing said oil and water into a heater at separate points; vaporizing the lighter ends of said oil adjacent one of said points while creating a region of nascent steam adjacent the other of said points and out of contact with said lighter ends; leading the unvaporized oil to said region to completely vaporize the same; and conveying the combined vapors of all of said oil and water out of said heater.

6. The method of vaporizing a hydrocarbon oil which consists in introducing a stream of said oil into a heater; separately introducing a stream of water into said heater; subjecting said oil and water to heat to vaporize the lighter ends of said oil at a point remote from said stream of water while simultaneously creating a region of nascent steam at the end of said stream of water; and leading the unvaporized oil to said region to completely vaporize the same by the action of said heat and nascent steam.

7. The method of vaporizing a hydrocarbon oil which consists in introducing said oil and water into a heater at separate points; heating said oil out of contact with said water to a temperature above the boiling point of water adjacent one of said points while creating a region of nascent steam adjacent the other of said points; and leading the heated oil to said region to completely vaporize the same.

In testimony whereof I affix my signature.
BERNARD ORMONT.
